SKI-SLED

William C. Billings, Modesto, Calif.

Application February 14, 1950, Serial No. 144,121

9 Claims. (Cl. 280—12)

1

This invention relates to sled-like conveyances for descending snow-covered slopes under the impetus of gravity, and especially to those equipped with ski-like runners.

In the field of winter sports, I have found that there is no satisfactory equipment presently available for deriving the thrills of skiing in a sitting posture. The conventional type of coasting sled is useless on most mountain slopes, and the toboggan suffers from a variety of defects, among which the most important is the lack of directional control. The bob-sled can be used only on carefully prepared runways, and involves dangers which only the most daring and experienced of sportsmen are willing to undertake. Various types of sled-like conveyances embodying ski-like runners have been proposed, but so far as I am aware none has proven satisfactory in practice, and none is in general use.

In accordance with the present invention, however, I provide a sled-like conveyance for use in winter sports by practically anyone, whether skilled or unskilled in the art of skiing, whereby thrilling descents of snow-covered mountain slopes may be accomplished at high rates of speed in a sitting posture and with far less danger of injury than is true of skiing generally or even of tobogganing. Adequate directional control is provided for by the proper shifting of weight by the rider in somewhat the same manner as in skiing, though not requiring the skillful muscular co-ordination demanded when on skis.

Accordingly, it is a principal object of the present invention to provide a sled-like conveyance for use in winter sports upon which the rider may glide swiftly and safely down a snow-covered slope while in a sitting posture, and for which only a moderate degree of skill by the rider is required.

Other important objects are:

To provide such a conveyance which may be readily and effectively guided by the mere shifting of the rider's weight.

To provide such a conveyance of lightweight and compact form, so it may be easily transported from place to place and carried by the prospective rider without the expenditure of an undue amount of effort.

To provide a construction which shall be capable of quantity production at a reasonable cost.

Outstanding features of the invention reside in the provision of a main ski-like runner flanked at opposite sides by auxiliary, outrigger ski-like runners which are spaced apart from but rigidly

2

tied to the main runner within a common operative plane.

In preferred embodiments, a seat is set low upon the main runner, and low-set, longitudinally-extending, stabilizer bars project forwardly from the seat at opposite sides thereof for grasping by the rider and use in regulating his shift of weight from time to time during the ride. Outwardly flared grooves at the undersurfaces of the respective runners correlate with the stabilizing bars in affording directional control of the conveyance by shift of weight on the part of the rider.

Further objects and features of the invention will be apparent from the following detailed description of the presently preferred forms illustrated, by way of example and not of limitation, in the accompanying drawing.

In the drawing:

20 Fig. 1 represents a top plan view of a single seat conveyance pursuant to the invention;

Fig. 2, a side elevation;

Fig. 3, a bottom plan showing the grooves in the various ski-like runners;

25 Fig. 4, a transverse section taken on the line 4—4 of Fig. 1;

Fig. 5, a transverse section taken on the line 5—5 of Fig. 1; and

30 Fig. 6, a top plan of a dual seat tandem arrangement pursuant to the invention, the view being drawn to a reduced scale.

Referring to the drawing: in the single seater form of Figs. 1 to 5, a relatively long, ski-like main runner 10 is flanked by a pair of relatively short, ski-like, auxiliary runners 11 and 12. The three runners 10, 11, and 12 are securely fastened together by a rigid structural framework 13 made up of suitable members, such as angle irons 13a and 13b, and a suitable longitudinal member, such as channel 13c.

The angle irons 13a and 13b are preferably welded to opposite ends of the channel 13c, and are suitably affixed to the three ski-like runners 10, 11, and 12, intermediate the lengths thereof, 45 as by means of screws 14. Thus, such ski-like runners are rigidly held in spaced, substantially parallel relationship, with their smooth undersurfaces lying substantially within a single operative plane.

The framework 13 serves as a mount for, and is, in turn, reinforced by a pair of stabilizer bars 15, which are rigidly attached, as by welding, to opposite end portions, respectively, of the forward and rear transverse frame members 13a and 13b. Such stabilizer bars 15 serve as hand

grips for the rider during use of the ski-sled, and, to better provide for the rider shifting his weight for guiding purposes during descent of a snow-covered slope, advantageously converge from front to rear. They rise only a few inches from the upper level of the ski-like runners, and preferably slope somewhat upwardly from rear to front, as illustrated in Fig. 2, to govern the degree of forward lean of a rider during descent.

A seat 16 is mounted at a low level at the rear end of the framework 13, advantageously by bolting, at its rear, to a cross-member 17 upon which it rests, and, at its front, to a rearwardly inclined, standard 18, upon which it also rests. As so mounted, the seat 16 is immediately above the main runner 10 intermediate the length of the rearward half thereof.

The cross-member 17 spans and is conveniently attached to the rear ends of the stabilizer bars 15, resting thereupon, and, consequently, positioning the rearward portion of the seat 16 most advantageously with respect to such stabilizer bars. The standard 18 is conveniently an inverted U-shaped member having its legs welded to the sides of channel 13c of the framework 13. It preferably rises higher from the runners than do the stabilizer bars, so that the forward portion of the seat 16 is raised above the rearward portion, thereby giving a pronounced rearward slant to the seat, as illustrated, see Fig. 2. This aids the rider to maintain his equilibrium during weight-shifting and other phases of the descent.

For facilitating directional control of the ski-sled by the rider's shift of weight from side-to-side during descent of a snow-covered slope, it is desirable that the smooth undersurface of the long and centrally disposed main runner 10 be provided with a pair of longitudinally-extending grooves 19, which flare outwardly, as at 19a, along the rearward portion of the runner. Likewise, it is desirable, that the rearward of this runner be flared outwardly somewhat as illustrated. It is desirable, further, that the shorter auxiliary or outrigger runners 11 and 12 be each provided with a single, longitudinally-extending groove, here indicated 20 and 21, respectively, which is offset inwardly of the longitudinal central axis of the runner, and which flares outwardly along the rearward portion of the runner in a sweeping curve, here indicated 20a and 21a, respectively, that crosses to the opposite side of the runner. Preferably, the rear ends 11a and 12a of such auxiliary runners flare outwardly along the outer sides thereof, as shown.

During a descent, the rider sits on the seat 16 with his legs extended in front so that his heels are planted firmly against the forward transverse frame member 13a over the spaces 22 and 23 between the main runner 10 and the respective auxiliary runners 11 and 12. Such spaces are desirably less in width than the heel of a normal small-sized ski boot, such width depending, of course, upon whether the particular ski-sled or ski-plane is designed for adult or child, so that adjacent runners will support the heel free and clear of the riding surface of the snow. Use of an angle-iron for the transverse frame member 13a is highly advantageous, not only for the sake of added rigidity, but for the upstanding leg which acts as a foot rest, as well. The hands of the rider grasp the side rails or stabilizer bars 16, sliding forwardly or back to correspond with the degree of forward lean assumed at various stages of the descent. The proper extent of weight-shifting needed for directional

control has been found to be taken care of almost intuitively by the rider, right from the start. The structural characteristics of the conveyance are such that the rider is properly placed for best riding results by merely sitting and placing hands and feet in the positions provided. Control is practically automatic even for the amateur.

Referring now to Fig. 6, which illustrates a dual-seater form of the invention. It can be seen that the main runner 25 is made sufficiently long to accommodate two sets, 26 and 27, of auxiliary or outrigger runners, and two seats, 28 and 29, in tandem. Otherwise, the construction of this form of the invention is preferably identical with the single-seater form described hereinbefore.

Whereas this invention is here illustrated and described with respect to certain presently preferred specific embodiments thereof, it should be understood that various changes may be made therein and various other forms may be constructed on the basis of the teachings hereof, by those skilled in the art, without departing 25 from the protective scope of the following claims.

I claim:

1. A ski-sled comprising a main ski-like runner, a plurality of auxiliary ski-like runners flanking the main runner in spaced relationship at opposite sides thereof, the running surfaces of all of said runners lying in substantially a common plane; a rigid framework attaching said runners together, said framework having a forward transverse member and a rear transverse member; 30 a rearwardly-positioned seat mounted over and immediately above the main runner, so that the rider is positioned at a low level relative to the said running surfaces of the runners, said seat being mounted adjacent the said rear transverse member, and the forward transverse member providing a foot rest; and an elongate stabilizer means rising above the upper level of said runners and extending forwardly from said seat for grasping by the hand of a rider.

2. The combination recited in claim 1, wherein the stabilizer means comprise a pair of elongate bars rigidly attached at their opposite ends, respectively, to the transverse frame members at 35 respectively opposite sides of the seat.

3. The combination recited in claim 2, wherein the stabilizer bars are disposed at a level below that of the seat.

4. The combination recited in claim 3, wherein the stabilizer bars diverge outwardly from the 40 seat substantially to the forward frame member.

5. The combination recited in claim 4, wherein the stabilizer bars slope upwardly from the seat substantially to the forward frame member.

6. The combination recited in claim 5, wherein 45 the undersurface of the main runner is provided with a pair of rearwardly and outwardly flared grooves, and the auxiliary runners are provided with respective rearwardly and outwardly flared grooves.

7. The combination recited in claim 6, wherein the grooves of the auxiliary runners extend along the inner margins of the respective runners and cross to the outer margins thereof in a sweeping curve rearwardly of said runners.

8. The combination recited in claim 1, wherein 50 the undersurface of the main runner is provided with a pair of rearwardly and outwardly flared grooves, and the auxiliary runners are provided with respective rearwardly and outwardly flared 55 grooves.

9. The combination recited in claim 8, wherein the grooves of the auxiliary runners extend along the inner margins of the respective runners and cross to the outer margins thereof in a sweeping curve rearwardly of said runners.

WILLIAM C. BILLINGS.
